UNITED STATES PATENT OFFICE.

ALLEN S. PEARL, OF MAYWOOD, AND CHARLES A. JANSEN, OF CHICAGO, ILLINOIS,
ASSIGNORS TO DELTA-STAR ELECTRIC COMPANY, OF CHICAGO, ILLINOIS, A CORPO-
RATION OF ILLINOIS.

PLUG SWITCHING DEVICE.

1,169,187.

Specification of Letters Patent. Patented Jan. 25, 1916.

Application filed December 26, 1912. Serial No. 738,582.

To all whom it may concern:

Be it known that we, ALLEN S. PEARL and CHARLES A. JANSEN, citizens of the United States, and residing at Maywood and Chicago, respectively, in the county of Cook and State of Illinois, have invented certain new and useful Improvements in Plug Switching Devices, of which the following is a specification, reference being had to the accompanying drawings.

This invention relates to plug switching devices comprising a receptacle adapted to be fixed upon a wall or other suitable support and a plug connected by suitable wires 15 to a motor or other device requiring an electric current.

The object of our invention is to provide a new and improved construction of plug switching device of this type by reason of 20 which the plug may be more safely attached to the receptacle than can be done in the use of prior constructions, by reason of which the contacts of both members may be more fully insulated from each other, and 25 by reason of which the contacts of the plug member may be more readily removed and replaced.

It is another object of this invention to improve devices of this type in sundry de- 30 tails hereinafter pointed out.

The means by which we have accomplished these objects are illustrated in the accompanying drawings and hereinafter specifically described. That which we be- 35 lieve to be new is set forth in the claims.

In the drawings,—Figure 1 is a vertical central section through our preferred form of construction; Fig. 2 is a section taken on line 2—2 of Fig. 1; Fig. 3 is a section on 40 line 3—3 of Fig. 1; Fig. 4 is a central horizontal section through a modified form of our device; Fig. 5 is a section on line 5—5 of Fig. 4; and Fig. 6 is an enlarged detail of one of the contacts of the plug shown in 45 Fig. 4.

Referring to Figs. 1, 2 and 3, in which corresponding parts are indicated by the same reference characters,—10 indicates the casing of the receptacle, to the back of 50 which is suitably secured a base 11 formed of wood, rubber, fiber, or other suitable insulating material. 12 indicates a plate of suitable insulating material secured by

screws or in any other suitable manner to the base 11. The casing 10 is provided with 55 an opening 13 through which the wires 14 from a dynamo or other suitable source of electrical energy may be led into said casing where they are connected in any suitable manner to the receptacle contacts 15 which 60 are secured in any suitable manner in the plate 12. Each of the receptacle contacts 15 extends some little distance beyond the front face of the plate 12, as is best shown in Fig. 1. 16 indicates tubular insulating members 65 which surround the receptacle contacts 15 and extend outward from the face of said plate 12 a short distance beyond the ends of the contacts 15. 17—18 indicate the two parts of the casing of the plug member of our 70 improved switching device. 19 indicates a block of insulating material seated in the handle member 17 of the casing of the plug, and 20 indicates a similar block held by a flange 21 of the casing 18 and securely held in position next to the block 19. 22 indicates 75 plug contacts mounted in the block 19. As best shown in Fig. 1, the block 20 is provided with openings therethrough adapted to register with the openings in which the contact plugs 22 are positioned. Each of the 80 plugs 22 is provided with a socket 23, in each of which sockets 23 the end of one of the wires 24 is adapted to be secured by means of solder or in any other suitable 85 manner. The wires 24 extend through a suitable opening in the end of the handle member 17, from which point they lead to a motor or other device where an electric current is to be used. As best shown in 90 Fig. 1, the end of each of the contact receptacles 15 is bored out and the end of each of the contact plugs 22 is split so that the contact plugs 22 may be forced into close electrical contact with said contact receptacles 15, this being made possible by reason of the fact that the ends of the contact plugs 22 are of such a size relative to the openings 95 through the block 20 that the outer ends of the contact receptacles 15 with the insulation about them are free to enter said openings through the block 20. 25 indicates a lid of any suitable type hinged upon the casing 10 of the receptacle member. When the plug member is withdrawn from the receptacle, the contact receptacles 15 are sepa-

rated from each other by a comparatively wide gap and also by the insulation about said contact receptacles. When the plug is in operative position relative to the receptacle the block 20 serves to insulate the contact plugs 22 from each other and the contact receptacles 15 from each other so that there is no danger of an arc between any two of the contact plugs or contact receptacles. This complete insulation of the current carrying parts is of very great importance in a plug switching device designed for use with high voltage currents. Whenever it is desired to remove one of the contact plugs 22 for any reason, this can be done very easily by simply unscrewing the casing member 18 from the casing member 17, removing the block 20 and pulling the contact plug 22 out of the block 19 to the left in Fig. 1. Inasmuch as these contact plugs 22 are held in position in this way without the use of screws or other binding parts, repairs may be made much more easily than would otherwise be the case. Moreover, the absence of screws or other securing parts is of considerable importance from the standpoint of efficiency of the device when in use. In many constructions heretofore the metal parts by which the contact plugs have been fixed in the insulating bases have been instrumental in the development of leakage or short circuiting, especially during damp weather.

Referring now to Figs. 4, 5 and 6, which show a modification of the device of Figs. 1, 2 and 3, 26 indicates the casing of the receptacle, secured to the back of which is a base 27 of suitable dielectric material. 28 indicates a block of similar material secured in any appropriate manner to the base 27. 29 indicates contact receptacles mounted in suitable insulating casings 30 and secured in any suitable manner in said block 28. 31 indicates lead wires the ends of which are secured in any suitable manner on the block 28 and electrically connected to the contact receptacles 29. 32-33 indicate the casing members of the plug, binding between them the insulating blocks 34-35, as in the preferred form of construction, the casing member 33, however, extending beyond the outer face of the block 35. 36 indicates substantially rectangular blocks of copper or other suitable conducting material mounted in suitable openings in the block 35. 37 indicates contact plugs mounted in suitable grooves in the blocks 36. 38 indicates socket members secured by screws to the blocks 36, in recesses 39 in which the ends 40 of the wires 40 are secured by means of soldering or in any other approved manner, the said wires 40 being adapted to be connected at their opposite ends to a motor or other electrically-operated device. It will be readily understood by an inspection of

this modified form of construction that the same advantages set forth in connection with the preferred construction are present in the modification. The contact plugs 37 and the parts by which they are connected to the wires 40 are held in position between the insulating blocks 34 and 35 without the use of screws or other metallic parts which might lead to a break-down of the insulation. The insulating casings 30 protect the ends of the contact receptacles 29, and the tongue 41 forming a part of the block 35 forms an effectual barrier between the contact receptacles 29 which are slotted to receive the contact plugs 37, as will be readily understood, and also forms an effective barrier between said contact plugs 37 as they are being withdrawn from the contact receptacles 29.

While we have shown three contact plugs 35 in the preferred form of device and only two contact plugs in the modified form, we do not restrict ourselves to the precise number of parts shown in either form.

That which we claim as our invention, 90 and desire to secure by Letters Patent, is,—

1. In a plug switching device, the combination of a block of insulating material, a casing member in which said block is mounted, a plug contact mounted in said block and extending therefrom, a second block of insulating material having a recess 95 into which said contact plug extends, one of said blocks having an opening for the insertion of a wire adapted to be connected to said contact plug, and a second casing member mounted upon said second-named block having a screw-threaded connection with said first-named casing member whereby said two blocks are clamped together. 105

2. In a plug switching device, the combination of a block of insulating material, a contact plug mounted therein and extending therefrom, a second block of insulating material having a recess into which said contact plug extends, said first-named block having an opening therein for the insertion of a wire adapted to be connected to said contact plug, and means independent of said contact plug for clamping said two 115 blocks together, said second-named block extending beyond the end of said contact plug and the recess in said second-named block being larger than the end of said contact plug, whereby a contact receptacle 120 can be inserted over said contact plug and inside of said recess.

3. In a plug switching device, the combination of a contact receptacle, means for holding said receptacle in fixed position, means for connecting a wire to said contact receptacle, a block of insulating material, a contact plug mounted in a recess in said block and extending therefrom, means for connecting a wire to said contact plug 125

within said recess, a second block of insulating material having a recess into which the extending end of said contact receptacle extends, and means acting independently of 5 said contact plug for clamping said blocks of insulating material together for holding the contact plug removably in position extending into the recess of said second-named

block into engagement with said contact receptacle.
